UNITED STATES PATENT OFFICE.

CHARLES N. WURTH, OF CAMDEN, NEW JERSEY, ASSIGNOR TO JACOB LOEB, OF CHELTENHAM, AND MAX SCHOENFELD AND DAVID SCHOENFELD, BOTH OF PHILADELPHIA, PENNSYLVANIA.

EMBROIDERING-MACHINE.

SPECIFICATION forming part of Letters Patent No. 271,182, dated January 23, 1883.

Application filed August 15, 1882. (No model.)

To all whom it may concern:

Be it known that I, CHARLES N. WURTH, a citizen of the Republic of Switzerland, and a resident of Camden, in the State of New Jersey, one of the United States of America, have invented certain Improvements in Embroidering-Machines, of which the following is a specification.

My invention consists of certain improvements, fully described hereinafter, in the embroidering-machine for which J. Ebneter obtained patents in France December 9, 1873, and October 30, 1875, and in the United States August 8, 1882, No. 262,383.

15 In order that my improvements may be thoroughly understood, it has been deemed best to illustrate and describe the entire machine, sundry features of which are included in the aforesaid patents.

20 In the accompanying drawings, Figure 1, Sheet 1, is a front view of the machine; Fig. 2, Sheet 2, a view, drawn to a larger scale, of one end of the machine; Fig. 3, Sheet 3, a front view drawn to the same scale as Fig. 2, 25 portions of the machine being broken off at intervals; Fig. 4, Sheet 4, a plan view of Fig. 3, the embroidery-frame being shown in section, and the shaft for supporting the same being removed; Fig. 5, Sheet 5, a horizontal section 30 of the pattern-board and pantograph mechanism, drawn to an enlarged scale; Fig. 6, Sheet 6, a transverse section of Fig. 5 on the line 1 2; Fig. 7, Sheet 7, a section of the embroidery devices; Figs. 8, 9, 10, and 11, detached 35 views of parts of the machine; Figs. 12, 13, 14, 15, 16, 17, and 18, Sheet 8, views illustrating the detailed construction of parts relating to the looper; and Figs. 19, 20, 21, and 22, Sheet 9, views relating to the detailed construction of the friction-clutch and mechanism 40 connected therewith.

Referring to Figs. 1 and 3, the fabric, H, to be embroidered is stretched in a frame, H', upon pins or tenter-hooks, and the bar h and screws 3 are employed to properly stretch the said fabric. A pattern-board, D, is secured to the frame, and to this board is attached the pattern to be followed in embroidering the fabric. A pantograph-plate, S, is also secured to

the frame H', upon which the wheels, herein- 50 after described, act to move the plate and frame in any desired direction as the embroidering progresses, the line of the pattern being moved across the index-point I on the main frame A of the machine by the manipulation of the de- 55 vices which control the wheels, as hereinafter explained. In order to allow of this move- ment of the frame H' and its fabric, it is nec- essary that the former should be hung so that it will require a very slight effort to move it 60 up or down, or to the right or left, or diagonally, the movement being always in the same plane. To provide for this motion I make use of a stiff tubular shaft, B, having pulleys B' 65 B² B³, the said shaft having its bearings on anti-friction rollers or boxes on the standards 70 or frames A' of the machine. The shaft is preferably strengthened and stiffened by the brace-rods b' and central head, b. To the pul- ley B' is attached a strap carrying a weight, 75 b³, to counterbalance the frame and its attach- ments.

To the pulleys B', B², and B³ are attached straps 5, the lower ends of which are connected by screw turn-buckles or other adjusting de- 75 vices to the horizontal bar b⁴, which will be raised or lowered bodily and uniformly at both ends alike by the turning of the shaft B and its pulleys.

Upon each of the standards A' are guide- 80 bars c, adapted to small grooved rollers at the ends of the rod b⁴, which is thus prevented from moving endwise and permitted to move up or down with very little friction, Figs. 1 and 3. The frame H' is hung to this bar b⁴ 85 by rollers c' and c⁴, so that it can be moved freely endwise.

I prefer to journal the anti-friction roller c' to a bracket on the frame H', and to adapt this roller to a rail, c², above the bar b⁴, and to 90 journal the roller c⁴ directly to the bar b⁴, adapting this roller to a rail, c⁵, connected by adjusting-screws c⁶ to the frame H', so that the latter may be as level as possible. The lower edge of the frame H' is steadied by the bars 95 c⁷, passing in front of the vertical stationary bars c⁸.

It should be understood that the index-

pointer I is to be placed in the proper position in relation to the pattern, that the pantograph apparatus is to be placed properly for acting upon the plate S, and that the embroidering mechanism is adjacent to the fabric, and the distance between one set of embroidering devices and the next corresponds to the distance between one figure or pattern and the next similar figure or pattern on the fabric.

10 The tracer and pantograph are not movable upon the frame A; but the embroidering devices can be adjusted farther apart or nearer together to adapt the machine to different designs or patterns.

15 I will now describe the actuating mechanism, and the pantograph and embroidering devices.

The power is applied by a belt to the pulley C, and there is a friction clutch or coupling 20 between the said pulley and the main driving-shaft E, so that the shaft can be stopped by operating a lever, d, or by an automatic stop-motion, as described hereinafter.

On the shaft E there is a scroll-cam, e, having a block, 6, on its periphery, and d² is a pivoted stop connected by the links d' with the clutch-lever d, so that when said lever d is moved and the power disconnected the stop d² will be moved into the path of the block 6, 30 so as to prevent any further movement of the shaft.

As shown in the enlarged views, Figs. 19, 20, and 21, the pulley C is loose on the shaft E; but a hub, C³, is fastened on the shaft, and 35 is provided with levers C⁴, acting on guided friction-blocks C⁵ to move them outward against the interior of the flange of the pulley C, and cause the belt on said pulley to rotate the hub C³ and shaft E. The conical 40 sleeve C⁶ is operated by the lever d, and serves to move the levers C⁴ from each other and to apply the friction-blocks to the pulley, and when this sleeve C⁶ is retracted the springs C⁷ will draw the friction-blocks C⁵ away from the 45 flange of the pulley and allow the shaft E to be stopped.

It is necessary to relieve the pulley C from friction at such a time that the block 6 will reach the stop d², and thereby stop the machine 50 when the embroidering-needles are out of the fabric. I prevent the movement of the lever d, except during a small portion of the revolution of the shaft E, by a projection, d⁶, at the side of the said lever d, which projection, when 55 the machine is running, is adjacent to the edge of the cam e. In this edge there is a recess or notch, d⁷, which extends as far as the arrows 1 indicate in Fig. 21. When the notch is at the projection d⁶ of the lever d the latter can 60 be moved, but at no other time.

The several parts are so arranged that after the projection enters the notch the block 6 will, as the shaft revolves, come in contact with the stop d² and be caught by its spring-latch.

65 The block d⁸, which is on a spring and forms part of the periphery of the cam e, is raised by

running upon the projection d⁶ as the parts are arrested. This block in its normal position partially fills the notch d⁷, so as to prevent the lever d being moved when the stop 6 has arrived too close to the end of the stop d².

It should be stated here that as far as the above-described stopping devices are concerned an ordinary plain pulley might be used in place of the cam; but as the latter is required for other purposes I have availed myself of its presence to perform the above-described duties.

The pantograph device comprises the appliances for giving such motion to the traversing frame and its fabric that the line of the pattern on the pattern-board D will, as the said pattern moves with the frame, always coincide with the stationary index-point I, Fig. 5. As the immediate means of traversing the frame, 80 I make use of two small steel wheels, e' e², with narrow edges, which are roughened or milled, the wheel e' being the actuating power-driven wheel for bearing against the front of the plate S of the frame, and the opposite wheel, e², being simply a pressing-wheel (not power-driven) for keeping the plate S against the wheel e', as will be seen hereinafter. These wheels are journaled to jaws e³ e⁴ on transverse shafts e⁵ e⁶ in head-stocks e⁷ e⁸ upon the front 85 frame, A, and back frame, A², respectively. (See Figs. 5 and 6.) There is a center screw, 8, to resist end-pressure upon the shaft e⁵, and a spring, 9, to apply end-pressure against the rear end of the shaft e⁵, thus causing the wheel 90 e² to force the pantograph-plate S against the wheel e'.

The jaws and shafts can be turned simultaneously, as hereinafter described, so that the wheels e' e² shall always revolve in the same 105 plane with relation to each other, and to the wheel e' a continuous and slow revolving motion is given. Hence the plate S and the embroidery-frame will be moved up or down, to the right or left, or diagonally, according to 110 the direction of the planes in which the wheels revolve, for the plate S will always be moved in the same direction in which the narrow edge of the wheel e' is rotating.

To give the desired rotary motion to the 115 wheel e' a worm-wheel, f, is secured to the shaft of the wheel e'; or there may be intermediate gear-wheels within the jaws, as shown by dotted lines in Fig. 5, and there is a worm, 10, (see Fig. 6,) and a gear-wheel, f', driven 120 by a pinion, f², loosely mounted on the shaft e⁵, and this wheel and pinion f², which has two sets of teeth, receive motion from the main shaft E through the train of gearing f³ f⁴, short shaft, and bevel-wheels f⁵ f⁶.

A shaft, g, extends longitudinally over the frame A, and another shaft, g', over the frame A², and these are connected together by gears h' h² h³, Figs. 1, 3, and 4, so that the two shafts will move in the same direction and at the 130 same speed.

On the shaft of the index-pointer I there is

a crank-handle, k , and a bevel-wheel, k' , on the shaft gears into a similar wheel, k^2 , on the shaft g . These wheels having the same number of teeth, the shafts g g' will be turned at 5 the same speed as the handle.

On the shaft e^5 of the jaw e^3 there is a wheel, l , with inclined teeth, and on the shaft g is a similar wheel, l' , and there are bevel-gears l^2 l^3 , by which the shaft g' is geared to the shaft 10 e^6 of the jaw e^4 . When the crank-handle k is horizontal the jaws e^3 and e^4 and the pantograph-wheels e^1 and e^2 will lie horizontal, and hence the wheel e' will move the plate S and embroidery-frame horizontally, and a horizontal 15 line on the pattern will move along behind the index-point I , and when the handle is inclined or vertical the wheel e' will be turned and cause the plate S and frame H' and cloth to move in the direction or inclination of the 20 handle. Hence the attendant has to turn the handle-crank in the direction of the line of the pattern or figure, and the wheel e' will move the plate S , embroidery-frame, and pattern-plate to cause the pattern-line to move along against 25 the index-point I , and hence each line of embroidery will correspond to the line of the pattern, and the most complicated pattern can be followed, and the lines of pattern and embroidery can cross each other or be led in any 30 direction, and the line of chain-stitching will be regular and progressive from one stitch to the next in the most perfect manner, both as to the length of stitch and its formation.

There is a shaft, g^3 , with a cam, g^4 , adjacent 35 to the spring 9 , Fig. 6, and an arm on the shaft is connected by a link, g^5 , to the lever g^6 , Fig. 2, so that by moving this lever the spring 9 , shaft e^6 , and wheel e^3 will be moved back and the plate S liberated, so that it will not be 40 moved by the rotation of the wheel e' , the frame and fabric being thus at liberty to be moved by hand in adjusting the same before the embroidery is commenced.

I will now describe the sets of embroidering 45 devices and their connection with the pantograph device.

As before remarked, there may be any desired number of embroidering devices; but as they are all alike I will limit my description 50 to one.

The needle i , Figs. 7 and 8, has a hook like that of a crochet-needle, and is fastened in the end of the needle-bar 15 , which can reciprocate in the tubular spindle o , which has 55 its bearings in a head-stock, o' , secured to the bed A , and held in position by a clamping-screw, 21 , the head of which is within an undercut slot in the top of said bed A . The needle-bar 15 and tubular shaft o will turn together, owing to a cross-piece, i^{10} , on the needle-bar being adapted to a slot in the tubular shaft; or any other equivalent device may be used for permitting the needle-bar to reciprocate in the tubular shaft, but compelling it to 60 turn therewith; and the shaft g is geared to the tubular spindle by wheels n n' , so that the

needle will be oscillated at the same time and in the same proportion as the tubular spindle o and jaw and roller e' , to keep the hook of the needle in the proper position to hold the 70 loop of thread as the fabric is moved between the respective stitches.

Upon the shaft E there are cams m , which give motion to the arms R R^3 and rock-shaft R' , and R^2 are arms upon this rock-shaft to 75 give end motion to the needle-bar 15 and needle i at the proper time to thrust the needle through the fabric, and then withdraw it with the loop of thread. The arms R^2 are made in two parts, connected by a bolt passing through 80 a slot in one of the parts, as shown in Figs. 7 and 9, so that the movement of the needle of any embroidering device may be discontinued by depressing the upper part of the arm out of contact with the collars on the needle-bar 15 . 85

A bracket, o^2 , projects from the head-stock o' , and in this bracket slides the tubular presser r . The needle i passes through this presser r , and there is a spring, r' , to force the same toward the fabric H . 90

The rock-shaft t is provided with an arm, t' , and upon the shaft E is a cam, t^2 , which, in connection with the spring last referred to, gives a vibrating motion to the rock-shaft t at the proper time; and there are forked arms t^3 on 95 this rock-shaft—one for actuating each presser, to draw back the same from the fabric after the needle, with its loop of needle-thread, has been retracted into the said presser. Each thread is on a spool. Each spool p is supported upon a std, p' , and has a friction-plate, 75 , to control the tension of the thread. 100

p^2 is a spring-eye for the thread to run through, and the thread passes into a tubular rotating looper, q , which has its bearings in 105 the head-stock q' , the latter being adjustable on the frame A^2 , so that the axis of each rotating looper q can be placed in line with each crocheted hook i .

There is a small plate, q^2 , at the end of the 110 head-stock q' , and this plate has a hole for the passage of the hooked needle i , Fig. 12. The fabric rests against this plate while the needle passes through it, and the plate is in vertical dovetailed grooves in the end of the 115 head-stock q' , (see Figs. 12, 14, and 18,) so that it can be drawn up and taken out to facilitate the introduction of the thread through its central hole. These stitch-plates can be changed, when necessary, to accommodate 120 larger or smaller threads. The levers or turn-buckles q^4 hold these plates down when in place, and can be turned aside to allow for their removal. 125

Each looper q is provided with a neck, into which enters the edges of a forked plate, q^6 , held by a screw to the head-stock q' , (see Figs. 12, 14, and 15,) so as to hold the looper in place and permit it to be withdrawn by loosening the screw and raising this plate. 130

As before stated, the shaft g' is rotated at the same time as the shaft g by the operator

as he moves the handle k , and this shaft g' , through the medium of the wheels 31 and 32, turns the loopers q and gives to the same their proper positions in relation to the hooks of the crochet-needles i , so that the latter will catch the threads. It is necessary also to give to the loopers q a partial or complete rotation for each stitch, so that the respective loopers partially wind or wrap the threads around the needles above the hooks, and thereby insure the catching of the threads by the hooks and the drawing of said threads through the fabric. I employ the same shaft, g' , for giving this partial rotation to all the tubular loopers q by communicating to the shaft g' an end motion for each stitch. This end movement is given by the lever q^5 and groove 35 in the scroll-cam e , which has been previously referred to, the lever q^5 having at one end a pin or roller adapted to the groove, and at the other end a rod, q^6 , which is in line with the shaft g' , and is connected thereto by a ball-and-socket joint, 37, the latter permitting the rotation of said shaft g' while it reciprocates.

The wheels 31, having inclined teeth, are secured to the shaft g' , and hence reciprocate endwise with it and oscillate the loopers q ; but the said shaft g' slides through the wheel l^2 , and there is either a feather on the shaft or a cross-piece, 40, acting against the parallel arms 41, which project from the tubular shaft of said wheel l^2 , so that the wheel will be turned with uniformity as the shaft g' is rotated, but will not be influenced by the reciprocating motion of said shaft.

Near the outer end of the shaft g' there is a cross-piece, 44, Fig. 4, on the said shaft, sliding upon the parallel arms of the fork 45 upon the short portion of the shaft carrying the wheel h^3 , so that the shaft g' may reciprocate endwise freely, but will receive its rotating motion from the wheel h^3 , for the purposes before described.

To stop the machine automatically I employ the following devices: The shaft v , Figs. 2 and 4, is rotated continuously by the belt v' , passing round the pulley 51 and round a pulley on the driving-shaft E , and the lever d , before mentioned in describing Figs. 19, 20, and 21, extends to this shaft v , where it terminates as a fork adjacent to a hub, 50, attached to the said shaft, so as to slide endwise on the same, but turning therewith. The pulley 51 has radial inclines or cams on its side, which are adapted to similar inclines at the end of the hub 50, and this pulley 51 is between a collar on the shaft v and the said hub. The shaft v can be revolved freely by the belt; but if the shaft is stopped the inclines on the hub and pulley cause the latter, as it revolves, to force the hub endwise on the shaft, move the lever d , and release the driving-pulley C . At the same time the stop d^2 is moved into the path of the projection 6 on the cam e , and the machine will be stopped in the manner described above. The lever d , however, can only move

when the notch d^7 is opposite to d^6 , the same as when moved by hand, Figs. 19 and 21. This shaft v and the whole machine are stopped when any one of the threads breaks. This is effected through the medium of the arms v^2 , which hang loosely on the shaft v^3 , each arm having a finger, v^4 , resting upon the thread, as shown in Fig. 7. If the thread fails to support the finger, the latter falls and the stop-arm v^2 drops into the path of the cam 56 on the shaft v , and hence arrests the movement of said shaft v and brings into action the before-described stopping mechanism.

An arm, 57, Figs. 2 and 4, situated conveniently for the attendant stationed at the pantograph device in front of the machine, is pivoted to the frame, and connected to one of the arms v^2 through the medium of a link connected to an arm on the shaft v^3 , to which the said arm v^2 is secured, so that the latter may be operated by hand to stop the machine.

In order to raise the fingers v^4 and hold them and the arms v^2 away from the influence of the cams 56, I provide arms 60, Fig. 7, which extend from the shaft v^3 and have a wire, v^6 , passing from one arm to the other beneath the fingers v^4 , Fig. 4, and an arm at the end of the shaft v^3 is connected by a link, 61, to the hand-lever 62, Fig. 2, by means of which the said shaft v^3 can be turned to move the arms 60 and lift the said fingers v^4 from the threads.

It is important to be able to adjust each needle without having to disturb the driving-wheels appertaining to the same, and to change the needles and replace any that may be broken. The cross-block i^{10} , Fig. 8, on the needle-bar is so clamped in place that the hook of its needle stands in the same direction as the hooks of the other needles, and the collars and jam-nut i^{11} can be screwed endwise on the needle-bar to adjust the needle-stock and needle endwise.

It is important to be able to draw the hooks of the needles entirely into the pressers r , so that they will be out of the way of the fabric while it is being stretched in the frame. I therefore employ a roller, o^{11} , Fig. 10, on the crank-pin o^{10} of the arm R^3 , and provide a clutch, o^{12} , by which the roller can be slipped endwise and held either in position for the cam m to act upon such roller or out of the way of the cam. When the roller o^{11} is thus drawn back the arm R^3 and the rock-shaft R' can be swung by hand until the crank-pin o^{10} touches the cam m . This will give to the arms R^2 and needle-bars an additional backward movement to bring the needles entirely within the presser.

I claim as my invention—

1. The combination, in an embroidering machine, of the following elements, namely: first, a traversing frame carrying the fabric to be embroidered, and having a plate, S ; second, a pantograph-wheel, e' , and mechanism for operating the same; third, a wheel, e^2 , journaled to a presser-bar; and, fourth, a spring

for acting on the said bar, and thereby forcing the wheel against the plate and the plate against the wheel e' , all substantially as set forth.

5 2. The combination of the embroidering-frame and its plate S, the shaft e^5 and its pantograph-wheel e' , and the shaft e^6 , carrying the wheel e^2 , with mechanism whereby the said shafts are geared together, so that both wheels 10 shall always revolve in the same plane, with mechanism for rotating the wheel e' only, the wheel e^2 deriving its rotating movement from the plate, substantially as specified.

3. The combination of the shaft e^6 and the 15 wheel e^2 , journaled thereto, the spring 9, secured to the frame and loosely connected to and bearing against the said shaft, and a cam, g^4 , for retracting the shaft through the medium of the spring, substantially as described.

20 4. The combination, in an embroidering-machine, of the following elements, namely: first, a frame carrying the fabric to be embroidered, and having at one end only a metal plate, S; second, mechanism whereby the said 25 frame is suspended and permitted to be moved in any direction in the same plane; third, a single pantograph-wheel and mechanism for revolving the same continuously, and causing it to act on the plate and traverse the embroidery-frame; fourth, a shaft carrying an index-pointer directed to the pattern-board; and, fifth, mechanism whereby the said index-shaft is caused to determine the plane in which the pantograph-wheel shall revolve, all substantially as described.

30 5. The combination of the shaft B, its counter-balances, pulleys B^2 and B^3 , and the bar b^4 , connected to the said pulleys by bands 5^5 , with the embroidering-frame having a roller, 35 c' , bearing on a rail on the frame, and an adjustable rail, c^5 , bearing on a roller, c^4 , secured to the frame, all substantially as set forth.

6. The combination of the tubular shaft o , the needle-bar 15, adapted thereto, the shaft R' , 40 its arm R^2 , and arms R^3 , with the driving-shaft E and cams thereon for imparting a positive reciprocating motion to the needle-bar through the medium of the arms, all substantially as set forth.

50 7. The combination of the arm R^3 on the shaft R' , and the cam on the shaft E for operating the said arm, with a roller, o^{11} , made adjustable on the pin o^{10} of the said arm, substantially as specified.

55 8. The combination of the head-stock q' and its tubular looper with the removable plate q^2 ,

having a hole for receiving the crochet-needle, and with a device for retaining the plate in place, substantially as described.

9. The combination of the head-stock q' and 60 its tubular looper, grooved at one end, with the detachable plate q^6 , which is adapted to the groove of the looper, and the removal of which permits the withdrawal of the said looper from the head-stock, substantially as specified. 65

10. The combination, in an embroidering-machine, of a series of tubular loopers, a stopping-shaft, r , common to the whole of the loopers, and a cam, 56, on the said shaft for each looper, with a lever adjoining each looper, and 70 having one arm v^2 adapted to a shoulder on the cam, and a finger for bearing on the thread, substantially as described.

11. The combination of the driving-shaft E of an embroidering-machine, a driving-pulley, 75 and braking or clutching appliances connected therewith, with a lever for applying the brake, and a pulley secured to the shaft and having a recess for receiving the lever and for determining when, during one revolution of the 80 shaft, the lever can be used as a medium for withdrawing the braking or clutching mechanism from the driving-pulley, all substantially as set forth.

12. The combination of the said recessed 85 wheel or pulley on the driving-shaft, and a block thereon, with a brake or clutch lever, and a stop so connected therewith that the stop will be moved within range of the block when the lever withdraws the brake or clutch, substantially as set forth. 90

13. The combination of the driving-shaft, the recessed wheel or cam thereon, the brake-lever, and a block, d^8 , applied to the pulley or wheel where the recess occurs, substantially 95 as described.

14. The combination of the stop-shaft v , a power-driven loose pulley, 51, having a hub with inclined teeth, a sleeve, 50, with corresponding inclined teeth on the said shaft, a 100 spring for maintaining the hub in gear with those of the pulley, and the brake-lever actuated by the sleeve, all substantially as specified.

In testimony whereof I have signed my name 105 to this specification in the presence of two subscribing witnesses.

CHAS. N. WURTH.
